C. S. PATTERSON

ROTARY TOOTHBRUSH

Filed April 27, 1923

INVENTOR.
Charles S. Patterson.

BY R. U. Smith.

ATTORNEY.

UNITED STATES PATENT OFFICE.

CHARLES S. PATTERSON, OF LANCASTER, CALIFORNIA.

ROTARY TOOTHBRUSH.

Application filed April 27, 1923. Serial No. 634,991.

To all whom it may concern:

Be it known that I, CHARLES S. PATTERSON, a citizen of the United States, residing at Lancaster, county of Los Angeles, State of California, have invented new and useful Improvements in Rotary Toothbrushes, of which the following is a specification.

This invention is a power driven rotary tooth brush, and it is the object of the invention to provide an instrument which may be conveniently held in the hand, and which is provided with a suitable drive mechanism adapted to be detachably connected to a rotatable brush having a guard for the same, the opposite end of the drive mechanism being adapted to be detachably connected to a usual flexible cable leading from an electric motor or the like.

It is a further object of the invention to provide means for readily reversing the direction of the rotation of the drive mechanism, without necessitating reverse rotation of the driving cable, and to provide a construction permitting of the interchangeable use of a plurality of brushes.

It is a still further object of the invention to provide an instrument having a straight handle provided with an angularly offset end adapted to support the brush with its axis in longitudinal alinement beyond the same, so that the device may be conveniently held in position with the side of the brush against the teeth, the guard for said brush being adapted to be mounted upon the handle at diametrically opposite points so as to overlie one side or the other of said brush.

The invention will be readily understood from the following description of the accompanying drawings, in which:

Fig. 1 is a top view of the instrument.

Fig. 2 is a side elevation of the same.

Fig. 3 is a section on the line 3—3 of Fig. 2.

Fig. 4 is a section on the line 4—4 of Fig. 1.

Figs. 5, 6, and 7 are transverse sections on the lines 5—5, 6—6, and 7—7 of Fig. 3.

Fig. 8 is a side elevation of the rotatable brush showing the guard for the same in vertical section.

Fig. 9 is a transverse section on the line 9—9 of Fig. 8.

Fig. 10 is an end elevation of the guard for the brush, partly broken away.

Fig. 11 is a vertical section through the connecting member adapted to engage the rotatable brush.

Fig. 12 is an end elevation of the same. The handle of the improved brush comprises a straight casing 1, preferably having a hinged side 2 forming a door which is adapted to be held in closed position by a catch 3.

An angular extension is formed at the front end of the handle, and preferably comprises a straight casing 4 having one end received in the end of casing 1, and its other end terminating in an angular offset 4' projecting beyond casing 1. The casing 4—4' is preferably square in cross-section and has a cylindrical bore extending through the same.

Transverse partitions 5 are provided in casing 1, and a shaft 6 is journaled in said partitions, said shaft being provided with collars 7 adjustably fixed thereon by set screws 8, and adapted to abut against the facing sides of said partitions, for adjustably fixing the shaft longitudinally of the handle casing.

A pinion 9 is fixed upon one of the collars 7 and is adapted to mesh with a pinion 10 upon a shaft 11 which is journaled in partitions 5 parallel to shaft 6. Suitable openings are provided in the end wall of casing 1 in alinement with the ends of shafts 6—11, and said shaft ends are squared as shown at 12, so as to be selectively engaged by the slotted spring end 13 of a flexible cable 14 which is rotated by a usual electric motor or the like (not shown).

An axially yieldable, flexible, rotary driving connection is provided in the bore of casing 4—4', and is shown as a coiled spring 15, the inner end of which is secured to a connecting member 16 having a squared socket adapted to receive the end of shaft 6 which is correspondingly squared, and the outer end of spring 15 is secured to a connecting member 17, rotatably mounted in the end of the bore of casing 4', and having a socket 19 which is preferably conical and corrugated.

A guard for the rotatable brush of the instrument is mounted on the end of casing 4', and comprises an arcuate plate 20 the length of the brush, and end walls 21, the front end wall forming a bearing socket 22,

and the rear end wall supporting a squared collar 23 adapted to be received over the end of casing 4'.

The rotatable brush comprises a center 5 rod 24 supporting bristles 25 forming a cylindrical brushing surface, and the front end of rod 24 is removably journaled in bearing 22, with the rear end of said rod adapted to be slipped through collar 23 and 10 into the end of casing 4', with said rod end forming a conical, corrugated bearing pin 26 adapted to be received in socket 19.

Projections 27 are provided at opposite sides of collar 23, either one of which is 15 adapted to be engaged by a spring catch 28 upon casing 4', so that by turning the brush guard until one or the other of said projections are in alignment with the spring catch, and then slipping collar 23 onto the end of 20 casing 4', the spring catch will engage the aligned projection to lock the guard in place, and the guard will be positioned so as to overlie one side or the other of the rotatable brush.

25 The construction as thus described permits of the interchangeable use of a plurality of brushes in the handle and guard structure, a brush being placed in the instrument by slipping bearing pin 26 through collar 23 and into socket 19, and moving connecting member 17 rearwardly against the tension of spring 15, until the outer end of the center rod of the brush may be slipped into bearing 22. The brush is then released so 30 that the spring 15 may force the same forwardly to hold it in place. To remove the brush, it is forced rearwardly against the action of spring 15, until the center rod 24 disengages bearing 22, so that the rear end 35 of said rod may be slipped out of collar 23.

With the brush in place, it is adapted to be rotated by the driving connection provided between shaft 6 and connecting member 17, said shaft being rotated in either 45 direction as desired, by connecting the drive cable 14 to either shaft 6 or to reversing shaft 11.

I claim:

1. A rotary tooth brush comprising 50 rotary drive mechanism, a driving connection operably connected to said drive mechanism, an axially yieldable spring forming a rotary operating connection between said drive mechanism and said driving connection and tending to move said driving connection axially away from said drive mecha-

nism, a bearing fixed relative to said drive mechanism axially beyond said driving connection, and a rotatable brush adapted to be journaled in said bearing at one end and 60 having means adapted to detachably engage said driving connection at its other end.

2. A rotary tooth brush comprising a handle, rotary drive mechanism journaled in said handle, a driving connection journaled in said handle axially beyond said drive mechanism, an axially yieldable spring forming a rotary operating connection between said drive mechanism and said driving connection and tending to move said 65 driving connection axially away from said drive mechanism, a guard mounted on said handle and forming a bearing axially beyond said driving connection, and a rotatable brush adapted to be journaled at one 70 end in said bearing and having means at its opposite end adapted to detachably engage said driving connection.

3. A rotary tooth brush comprising a handle having an angularly offset end, drive 75 mechanism journaled in the main portion of said handle, a driving connection journaled in said offset end, a yieldable flexible operating connection between said drive mechanism and said driving connection, 80 tending to move said driving connection axially away from said drive mechanism, a bearing fixed relative to said handle and said drive mechanism axially beyond said driving connection, and a rotatable brush 85 adapted to be journaled in said bearing at one end and having means adapted to detachably engage said driving connection at its other end.

4. A rotary tooth brush comprising a 90 closed casing forming a handle, a drive shaft journaled in said handle, a brush journaled at the front end of said handle and operatively engaged by said drive shaft for 95 rotating said brush, a reversing shaft journaled in said handle parallel to said drive shaft, and meshing pinions on said shafts, the rear end of said closed handle casing having openings in alignment with the respective shafts adapted to selectively receive rotary operating mechanism, and the rear ends of said shafts having connections adapted to be operatively engaged by said rotary operating mechanism.

In testimony whereof I have signed my 100 name to this specification.

CHARLES S. PATTERSON.
